UNITED STATES PATENT OFFICE.

PHILIP CARTER BROWN, OF DOVER, NEW HAMPSHIRE.

LEATHER-STRETCHING MACHINE.

1,299,672.

Specification of Letters Patent.

Patented Apr. 8, 1919.

Application filed October 7, 1916. Serial No. 124,436.

To all whom it may concern:

Be it known that I, PHILIP CARTER BROWN, a citizen of the United States, residing at Dover, in the county of Strafford and State 5 of New Hampshire, have invented certain new and useful Improvements in Leather-Stretching Machines, of which the following is a specification.

My invention relates to leather stretching

10 machines, *i. e.*, to machines for stretching skins, hides, or pieces of leather, especially such pieces as are to be used for making belting. My invention relates more particularly to machines of this general type in 15 which opposite ends of the leather are gripped by clamping devices or clamps which are spaced apart and adapted to be relatively drawn away from one another so as to put the leather under tension. Each 20 clamp commonly comprises an upper jaw and a lower jaw and is provided with means for bringing the jaws forcibly together upon the leather so as to hold the same without slip.

25 In the prior art, machines of this kind have been provided with clamp members or jaws of cast iron, the opposed faces thereof being formed, respectively, as a single convex and concave surface (the two faces being, hence, complementary to one another) so as to insure a good grip upon the leather. In some cases the clamp members, instead of having complementary curved surfaces, have been formed with V-shaped teeth, each 30 jaw having sometimes one and sometimes a plurality of teeth. Where a plurality of V-shaped teeth have been employed, however, the distance from tooth to tooth has been substantially less than the thickness of 35 the leather to be stretched. In still other cases, no attempt has been made to provide special gripping surfaces for the clamp members but various special and independent holding devices have been inserted between each clamp member and the leather.

40 Where jaws having plane or simple curved surfaces have been used, it has been impossible to hold the leather securely except by

giving the jaws a very considerable width. Since that portion of the leather lying between the jaws has not ordinarily been stretched, it must be cut from the stretched portion and is therefore waste for which some special use must be found if it is to have any value. Where the jaws are provided with V-shaped teeth, the jaws may, indeed, be made narrower but that portion of the leather between the jaws becomes so gashed and mutilated by the sharp edges of the teeth that it is rendered valueless for 50 any practical purposes. And in the case where special holding devices are utilized between the clamp members, an undue amount of time is required in adjusting the devices in position with respect to the clamps 55 and the leather.

Another grave disadvantage attendant upon clamp members such as have been described, is the fact that the leather in contact with the clamps will be discolored or 60 blackened, due probably to chemical action between the iron and organic materials in the leather; or to chemical action between the iron and materials incorporated in the leather during the tanning and preliminary 65 treating process. This blackening or discoloration tends to be aggravated by reason of the currying grease and water forced from the leather by the pressure of the clamps, which materials will also be blackened and 70 will spread over other regions of the leather so as to blacken and damage them as well. This blackening obviously greatly depreciates the value and salability of the leather 75 wherever it occurs.

80 In the case of any of the previously known types of clamp above referred to, the greases forced from the leather by the clamping pressure tend to diminish the grip between the clamps and the leather and hence to 85 permit the leather to slip. This tendency to slip compels either a correspondingly increased width of clamp or a more pronounced tooth surface, and hence accentuates the disadvantages already referred to.

90 One object of my herein about to be de-

85

90

95

- scribed invention is to provide clamp members having faces or clamping surfaces of special shape such that they may be quite narrow and yet grip the leather without slip.
- 5 Another object of my invention is to provide that the shaped clamping surfaces just referred to shall hold the leather without mutilating its structure or seriously mal-forming its surface. Still another object of 10 my invention is to provide a material for the clamping members, or for the faces of said clamping members, which shall not re-act chemically, or otherwise, with materials contained in the leather so as to blacken or dis- 15 color the same and which at the same time is so hard and unyielding that it can be embodied in very narrow clamps of small cross-section to which very great pressures may be applied without danger of deforming the 20 clamps, whereby the leather may be very securely held.

Briefly described, my invention resides in providing clamping members for leather stretching machines having opposed complementary and interlocking faces, each of these faces comprising a plurality of smoothly curved flutes, as distinguished from teeth. The clamp members, or those portions of the clamp members which in- 30 clude the fluted faces, are made of nickel-bronze, preferably by the extrusion process, which material I have found will not stain or discolor the leather.

My invention will be better understood by 35 referring to the accompanying drawings in which Figure 1 represents a side elevation of a conventional leather stretching machine having my invention embodied therein; Fig. 2 represents a top plan view of the 40 machine shown in Fig. 1; Fig. 3 represents a top plan view, on a scale twice that of Figs. 1 and 2, showing the stretcher and the two stretching clamps; Fig. 4 represents the view shown in Fig. 3 in side elevation; Fig. 5 represents an elevation, part section, twice enlarged, taken from the left of Fig. 3; Fig. 6 is a view, similar to Fig. 5, taken 45 from the left of line 6-6 of Fig. 3; Fig. 7 represents a section taken along the line 50 7-7 of Fig. 6; Fig. 8 represents a section, similar to Fig. 7, taken along the line 8-8 of Fig. 5; Fig. 9 represents an end view taken from the right of Fig. 1; Fig. 10 represents, on an enlarged scale, a side 55 elevation of the hanger attached to the inner end of the stretcher; Fig. 11 is a section, twice enlarged, taken along the line 11-11 of Fig. 2; Fig. 12 represents, enlarged, a transverse section through a preferred 60 form of one of my improved clamp members, the same being shown in the several drawings as a removable insert; and Fig. 13 shows, on a greatly enlarged scale,

the shape of the recurring pair of flutes with which the gripping surfaces of my clamp members (as illustrated in Fig. 13) are provided.

In the drawings, a main frame 1 has mounted thereon, a longitudinally slideable cross head 2 which is engaged by a screw 3 70 having a bearing at 4 and carrying a gear wheel 5. Gear wheel 5 is in mesh with a similar smaller gear 6 fixed upon a shaft carrying two sets of pulleys, one set being larger than the other and each set comprising a tight pulley 7, 8, and a loose pulley 7', 8'. One of these sets is provided with an open belt and the other with a cross belt (neither belt shown), both belts being adapted to be driven from some suitable source 80 of power. These belts are adapted to be shifted from loose to tight pulleys, and vice versa, by a shift rod 9 and shift lever 10 in the usual way. The screw 3 may, therefore, be operated in one direction at a high rate 85 of speed and, in the other direction, at a low rate of speed. The cross head 2 will, hence, be correspondingly moved rapidly or slowly according to the direction of its movement.

At the left (Figs. 1 and 2) is an auxiliary frame 11 which, as also main frame 1, must be fixedly attached to the floor. Pivotedly attached to frame 11, at 12, is a stretcher 13 comprising a frame 14 of angle iron, the inner end of which, when this stretcher is in working position, rests upon one end of the main frame 1 (Fig. 2), while the outer end has attached weights 15 whereby, if the stretcher is swung into an upright position (dotted lines, Fig. 2) it tends to remain in such position.

The inner end of frame 14 is also provided with an attached trolley bracket 16 to which is fixed a short section of track 17.

The stretcher also comprises a stretching plank 18 which normally rests upon rollers 19 mounted in bearings fixed to the top of frame 14. Upon the upper side of this plank are mounted the two stretching clamps, the fixed clamp 20 (Figs. 5 and 8) at the outer end of the plank being tightly bolted thereto, and the remaining or loose clamp 21 (Figs. 6 and 7) being spaced from the fixed clamp and longitudinally slideable with respect thereto.

A draw rod 22 is bolted fast to each end of cross head 2 and the free end of each rod is formed as a hook 23, which lies against the outer side of the loose clamp 21 at its ends. As the cross head is moved to the right (Figs. 1 and 2) by the screw 3, it will carry the loose clamp with it.

Each clamp comprises two halves or jaws, the upper jaws being alike both for the fixed and for the loose clamp. The lower jaw 24 of the fixed clamp has lugs 25 which lie on each

side of the stretcher plank and enable the clamp to be bolted fast thereto. The lower jaw 26 of the loose clamp has similar lugs 25' whose extremities are bridged by a plate 5 27 so as to provide a slot by means of which the loose clamp is threaded over and made slidable upon the stretcher plank.

The ends of both clamps are provided with adjustable draw bolts 28 for bringing 10 the jaws forcibly together when desired, said jaws tending to open up and separate from one another when the bolts are unscrewed by reason of the action of the springs 29 one of which is threaded over each bolt between 15 the jaws.

The lower jaw 26 of the loose clamp also carries a pivotally attached pawl or dog 30 adapted to engage the teeth of a rack 31, which is fixed to the upper side of the 20 stretcher plank 18, when the pawl is thrown downwardly, and to be free of said rack when the pawl is thrown upwardly.

Slots are milled out in the opposed portions of the jaws of both the fixed and the 25 loose clamp. Each of these slots serves to receive an accurately fitted rib 32 formed, preferably integrally, on the back of an insert clamp bar 33 (Figs. 5, 6, 7, 8, 11, 12). This insert clamp bar is, preferably, of 30 nickel-bronze made by the extrusion process as I find this material to be exceedingly hard and homogeneous when thus worked and, furthermore, to be inert chemically with respect to leather, organic materials generally 35 found therein, and to the various oils, greases and other materials incorporated with the leather prior to the stretching operation.

The body of each insert clamp bar is 40 wider than the rib 32 and its inner face 34 is provided with a plurality of longitudinal flutes, these flutes being transverse to the stretching plank, therefore, when the clamp bar and clamp are in operative position 45 (Figs. 1 to 8). The shape of these flutes should be such that their intersection with a transverse plane will be defined by a smooth curve which will nowhere change its rate of curvature rapidly. In the particular embodiment used in the drawings I 50 have employed a sinusoidal curve (Figs. 13 and 14) made up of smoothly joined identical circular arcs 35 and 36, which lie respectively below and above the axis of ab- 55 scissæ 37-37, each arc subtending substantially an angle of 45°. Instead of this particular curve I may use any simple sine curve if I desire. In this particular curve the height of the curve at its crest is sub- 60 stantially equal to one-fifth the length of the curve from crest to crest; I find these dimensions to be satisfactory for use with all power belt stock including the heaviest.

For light weight stock the ratio of height of curve to length may be increased if desired, thus securing a greater gripping effect or enabling narrower clamps to be used.

It is imperative, whatever the shape of the curve, that the curves of the opposed 65 faces of the two insert bars should be identical so that the two faces may be accurately fitted into one another. This complementary relation is most conveniently attained by insuring that, whatever the shape 70 of the curve, that portion thereof lying above the axis of abscissæ shall be identical with the adjacent portion lying below said axis.

It is also imperative that the rate of 75 curvature of the flutes should be sufficient to insure that leather pressed between the clamps should be securely held without, however, being great enough to stretch the fibers on the convex side of the leather or 80 to compress fibers on the concave side of the leather, beyond their elastic limit.

I have found that the curve shown in Figs. 12 and 13, and previously described, will satisfy, for practically all power belt 85 stock ordinarily used, the requirements just above specified.

The inner end of main frame 1 is provided with a notched block 38 and the inner end of the stretching plank, when in operative 90 position, butts against the end of this block with the eye 39, which is bolted to the end of the stretching plank, lying in the notch.

A pulley 40, carrying a hanger from which is suspended a hanger link 41 en- 100 gaged with eye 39, normally rests within the trolley bracket 16 upon the track section 17.

The stretching machine being in operative position, as shown in Fig. 1, a strip of 105 leather to be stretched has its two ends placed between the fluted surfaces of the insert clamp bars of the fixed and loose clamps respectively; the draw bolts 28 are then tightened so as to bring the upper and 110 lower jaws together thus forcing the complementary surfaces of the opposed insert bars toward one another and compelling the leather to follow the shape or curve of the flutes. That is to say, the leather will be 115 forced down into each concave groove by the corresponding convex rib of the opposed insert bar. This will cause the leather to be gripped by each pair of bars with a wedging action due to the fact that the distance between the coöperating curves decreases at an increasing rate as the distance 120 from the central points (the highest and lowest points) of the curves increases.

Shift lever 10 is now thrown so as to 125 rotate the screw 3 at its lowest rate in the

direction to move the cross head 2 toward the outer end of the main frame 1 (to the right Fig. 1). The loose clamp 21 will, hence, be correspondingly moved in the 5 same direction through the action of draw rods 22, thus stretching the leather between the fixed and loose clamps. As the loose clamp is thus moved, the pawl 30 will slip over the teeth of rack 31, engaging each 10 tooth successively.

When the leather has been stretched to a sufficient extent the shift lever 10 may be thrown so as to reverse the motion of screw 3 and cross head 2. Pawl 30 will prevent the 15 loose clamp from slipping back and the leather will, therefore, remain in its condition of maximum stretch.

Hooks 23 will now be free of the loose clamp so that the inner end of the stretcher 20 may be thrown upwardly about its pivot 12 (as shown dotted in Fig. 1). In this position the track section 17 will fit into a gap of continuous trolley track (not shown) and the pulley 40 with the suspended stretching 25 plank and stretched leather thereon may be run off to one side. From the other side a second stretching plank, similar to the first, may be run into place upon track section 17 and the stretcher again thrown down 30 into operative position and a fresh piece of leather put into place and stretched. And so on indefinitely.

The leather may, of course, be removed 35 from the stretching plank whenever desired by merely slackening the draw bolts 28.

When the leather is thus gripped in my improved clamps as above described it is held without the slightest slip and yet without the application of excessive strains to 40 the draw bolts and clamps. There is, hence, no danger of breaking either bolts or clamps. And the leather, where it has been subjected to the gripping action of the insert bars, while it will have been smoothly fluted in 45 the pattern of the gripping surfaces of said bars, will have its surface unbroken and free from transverse lines of broken fibers such as are found when gripping surfaces comprising parallel teeth are employed. 50 Furthermore, these portions will be entirely free from any discoloration. They may, therefore, if suitably rolled out, be used on the under lap, where the leather stretched is a length of belting. And, except where 55 the highest finish is desired, they may be thus used on the top lap. And in any event, if these portions are not left on the belt or other article which has been stretched, they may be cut off and used for other suitable 60 purposes and will command nearly as good a price as if they had never been subjected to the described pressure.

It should be stated, furthermore, that the

portions of leather which lie between the fluted clamping surfaces during the stretching operation are themselves as fully stretched as those free portions of the leather which lie between the fixed and loose clamps. This arises from the fact that the leather is bent around and follows the curves 70 of the interlocking flutes.

Since the insert bars are inert to the greases and other materials which are 75 squeezed out of the leather these materials will not be stained or discolored and, hence, when they spread to portions of the leather adjacent to the clamps such portions will similarly remain unstained and free from discoloration.

The width of each flute should be, preferably, not substantially less than the thickness of the leather which is to be stretched as, otherwise, the leather will merely be indented without being bent around the flutes so as to conform to the shape of the space 85 lying between the clamping surfaces.

Having described my invention, I claim:

1. In a leather stretching machine, clamps the sections of whose opposed faces are complementary sinusoidal curves, the height of 90 which at the crests is substantially one-fifth the length of the curve from crest to crest, so that with respect to leather pressed between the clamps the fibers thereof on the convex side will be stretched, while, conversely, the fibers on the concave side will be compressed but, in either case, not beyond their elastic limit.

2. In a leather stretching machine, clamps the sections of whose opposed faces are complementary sinusoidal curves, the height of 100 which at the crest is so proportioned to the length of the curve from crest to crest that, with respect to leather pressed between the clamps, the fibers thereof on the convex side 105 will be stretched while, conversely, the fibers on the concave side will be compressed but, in either case, not beyond their elastic limit.

3. In a leather stretching machine, clamps whose opposed faces are provided with a plurality of smooth flutes, the shape of each fluted surface being such that its intersection with a transverse plane is a curve whose adjacent portions merge smoothly into one another and are alternately convex and concave, the faces being, further, complementary to one another and the dimensions of the curves being such that, with respect to leather pressed between the clamps, the fibers thereof on the convex side will be 115 stretched while, conversely, the fibers on the concave side will be compressed but, in either case, not beyond their elastic limit.

4. In a leather stretching machine, elongated clamps of nickel-bronze having 125 axially disposed complementary flutes which

serve as gripping faces, the rate of curvature of the flutes being such that leather pressed between the clamps will be held without permanent deformation.

- 5 5. In a leather stretching machine, clamp bars having a plurality of opposed fluted and complementary faces of nickel-bronze, the rate of curvature of the flutes being such that, with respect to leather pressed between the clamps, the fibers thereof on the convex side will be stretched but not beyond their elastic limit while the fibers on the concave side will be compressed but not beyond their elastic limit.
- 10 6. In a leather stretching machine, elong-

gated clamps of nickel-bronze having axially disposed complementary flutes whose sections are sinusoidal curves, the rate of curvature of which is such that leather pressed between the faces, while it will be 20 bent to conform with the shape of said faces will nowhere be bent sufficiently to deform the fibers beyond their elastic limit.

In testimony whereof I have hereunto subscribed my name.

PHILIP CARTER BROWN.
